BAG CLOSING AND SEALING MACHINE

John L. Knapp, St. Joseph, Mo.

Application January 27, 1940, Serial No. 316,019

17 Claims.

(Cl. 93—6)

This invention relates to bag closing and bag sealing machines for closing and sealing filled bags.

An object of this invention is to provide a machine adapted particularly for closing and sealing bags formed of cellulose material, such as Cellophane or the like.

Another object of this invention is to provide an improved method and means for closing and sealing filled Cellophane bags which includes initially holding the bag mouth open, forming a pair of longitudinal folds at the mouth end of the bag, closing the bag mouth by compressing the walls of the bag together at the mouth end, forming a transverse fold across the mouth end and finally sealing the transversely folded portion of the bag.

A further object of this invention is to provide intermittently operable mechanisms which are operable upon the bag in sequence, the mechanisms being timed in their operation through suitable cams, levers and gear trains to thereby act upon the bag at the proper time.

A still further object of this invention is to provide an improved mechanism which is adapted to initially act upon the bag mouth so as to prepare the bag for the succeeding operation and to release the bag just prior to the time the succeeding operation is effective.

Embodying the foregoing aims and to others which may hereinafter appear, the invention consists of the novel construction, combination and arrangement of parts as will be more specifically referred to and as illustrated in the accompanying drawings where in is illustrated an embodiment of this invention, but it is to be understood that changes, variations and modifications may be resorted to which fall within the scope of the invention as claimed.

In the drawings—

Figure 1 is a detailed front elevation partly broken away and in section of a bag closing and sealing machine constructed according to an embodiment of this invention.

Figure 2 is a fragmentary sectional view taken on the line 2—2 of Figure 1.

Figure 3 is a detailed end elevation partly broken away and in section of the sealing end of the machine.

Figure 4 is a sectional view partly broken away taken on the line 4—4 of Figure 1.

Figure 5 is a horizontal sectional view taken on the line 5—5 of Figure 1 showing the initial operation of the bag opening structure and also

showing the bag sealing structure in operative position.

Figure 5a is a horizontal section of a bag opening and holding means showing the manner of opening and folding the bag.

Figure 6 is a sectional view similar to Figure 5 but showing the bag closing structure in operative position and the sealing structure in inoperative position.

Figure 7 is a fragmentary end elevation partly in vertical section of the sealing device.

Figure 8 is a fragmentary rear elevation partly in vertical section of the machine.

Figure 9 is a sectional view taken on the line 9—9 of Figure 8.

Figure 10 is a fragmentary end elevation partly broken away and in vertical section of the bag opening and sealing mechanism.

Figure 11 is a sectional view taken on the line 11—11 of Figure 10.

Figure 12 is a sectional view taken on the line 12—12 of Figure 10.

Figure 13 is an enlarged fragmentary sectional view taken on the line 13—13 of Figure 6 showing the initial closing of the bag mouth.

Figure 14 is a view similar to Figure 13 but showing the transverse folding of the bag mouth.

Figure 15 is a fragmentary front elevation of one of the bag closing and folding members.

Figure 16 is a sectional view taken on the line 16—16 of Figure 3.

Figure 17 is a detailed front elevation partly broken away of a duplex bag closing and sealing machine.

Figure 18 is a bottom plan view of a rotary sealing structure.

Figure 19 is a fragmentary sectional view taken on the line 19—19 of Figure 18.

Referring to the drawings and first to Figure 1, the numeral 20 designates generally a combined bag opening and folding mechanism, the numeral 21 designates generally a combined bag mouth closing and folding mechanism, the numeral 22 designates generally a sealing mechanism and the numeral 23 designates generally a conveyor or bag shifting mechanism.

The mechanisms hereinbefore described are mounted on a frame structure generally designated as 24 which extends upwardly from a table 25 carried by a base structure 26. The frame structure 24 includes vertically disposed frame members 27 which are carried by a base 28 secured as by fastening devices 29 to the table 25 at the rear thereof.

The combined bag opening and folding mech-

anism 20 comprises a vertically shiftable slide or plunger 30 which is slidable in guide members 31 and 32 carried by forwardly projecting brackets 33 and 34, respectively, which are carried by the upright frame members 27. The slide or plunger 30 at the lower end thereof is provided with a pair of rock levers 35 and 36 which at their lower ends are provided with enlarged heads or plates 37 and 38, respectively. The plate or head 37 is provided on the opposite vertical sides thereof and on the forward side with pairs of vertically spaced apart forwardly projecting ears 39 and the plate or head 38 on its rear side is provided with pairs of rearwardly projecting ears 40. The rock lever 35 is rockably mounted on a pivot member 41 extending through the lower end of the plunger or slide 30 and the lever 36 is rockably mounted on a pivot member 42 also extending through the slide or plunger 30. The head 37 of the lever 35 has swingably mounted thereon a pair of bag opening fingers 43 which as shown in Figure 1 are normally disposed in downwardly convergent relation. The fingers 43 are provided with an angularly disposed extension 44 and a shaft 45 extending upwardly from the extension 44 which is rockably mounted in a pair of ears 39. The upper end of the shaft 45 terminates in an angularly disposed extension 46 provided with an inwardly projecting hook 47. The forward pair of extensions or arms 46 of the two forward fingers 43 are constantly urged inwardly toward each other by means of a contracting spring 48.

The arms or extensions 46 engage the opposite edges of a V-shaped cam or wedge 49 which is supported in outstanding relation to the lower end of the slide or plunger 30 by means of a supporting plate 50 formed with a flange 51 which is fixed by fastening devices 52 to the slide or plunger 30. By means of the cam member 49 when the lever 35 is rocked so as to swing the lower end thereof outwardly, the arms 46 will slide upwardly along the upwardly divergent edges of the cam 49 and thus rock the fingers 43 outwardly so as to thereby tension or hold taut one side of a bag member generally designated as B.

The head 38 is also provided with a pair of bag opening fingers 53 which are constructed similar to the fingers 43 and are provided at their upper ends with angularly disposed extensions 54. A shaft 55 is formed integral with an extension 54 and is rockably mounted in a pair of ears 40. An arm 56 similar to the arms 46 which is formed integral with the upper end of the shaft 55 is provided with a hook 57 at its rear end. A spring 58 engages the two hooks 57 carried by the two rear arms 56 and constantly maintains the arms 56 in sliding contact with a finger expanding or rocking cam 59 constructed similar to the cam 49. The cam 59 is provided at its upper end with an angularly disposed extension 60 having a flange 61 which is secured by fastening devices 62 to the rear side of the slide or plunger 30.

A second pair of rock levers 63 and 64 are carried by the slide or plunger 30 adjacent the lower end thereof, being mounted on outstanding ears 65 and 66, respectively, which are secured in outstanding relation to the lower portion of the slide or plunger 30 in a position above the two cam members 49 and 59. The levers 63 and 64 are provided with depending folding fingers 67 and 68, respectively, which are of substantially V-shaped configuration in front eleva-

tion and which are provided with relatively long upwardly projecting arms 69 and 70, respectively. The arms 69 and 70 are secured in any suitable manner to the lower ends of the levers 63 and 64. The upper end of the lever 63 is provided with a yoke 71 between the arms of which a roller 72 is rotatably mounted. The roller 72 engages against a cam 73 which is carried by the lever 36 above the pivot 42 and the roller 72 is constantly held against the cam 73 by means of a spring 74 which is secured at one end to an upstanding pin 75 carried by the yoke 71 and is also secured at the opposite end thereof to the slide or plunger 30.

The lever 64 is provided at its upper end with a U-shaped yoke 76 between the arms of which a roller 77 is rotatably mounted and the roller 77 engages against a cam 78 which is carried by the lever 36 above the shaft member 42. A spring 79 is secured at one end to the yoke 76 and at the other end to the plunger or slide 30 so as to constantly hold the roller 77 in engagement with the cam 78. The two springs 74 and 79 in addition to constantly urging the rollers 72 and 77 in engagement with the cams 73 and 78, respectively, constantly urge the folding members 67 and 68 outwardly to an inoperative position and in addition constantly urge the levers 35 and 36 to maintain the bag opening members 43 and 53 in an inoperative position.

A cam shaft 80 is rotatably carried by the frame structure 27 being journalled in bearings 81. The shaft 80 has a lever operating cam 82 fixed thereto and also has a gear 83 fixed to one end thereof. The cam 82 engages the lever 35 adjacent the upper end thereof and is adapted to effect rocking of the lever 35 upon rotation of the shaft 80. A second cam shaft 84 is journalled in bearings 85 carried by the frame 27 and has a cam 86 fixed thereto which engages the lever 36. A gear 87 is also fixed to the cam shaft 84 and meshes with the gear 83. The cam shaft 84 has fixed thereto a sprocket 88 about which a chain 89 engages. The chain 89 also engages a sprocket 90 carried by a horizontally disposed shaft 91. The shaft 91 is journalled in the frame 27 being disposed rearwardly of the slide member 30 as shown in Figure 3.

The shaft 91 has a sprocket 92 secured thereto about which a chain 93 engages. The chain 93 also engages a sprocket 94 carried by a shaft 95 disposed at the rear of the frame structure 27 and above the shaft 91. A sprocket 96 is also secured at the shaft 95 and a chain 97 engages about the sprocket 96 and also about a driving sprocket 98 which is fixed to a driving shaft 99. The drive shaft 99 as shown in Figure 3 is journalled in the rear of the frame structure 27 and as shown in Figure 8 a driving sprocket 100 is fixed to the shaft 99 and is adapted to be connected to a suitable source of power supply.

The plunger or slide member 30 is vertically moved by means of a rock lever 101 which is rockably mounted on a support 102 extending between the two brackets 34. The lever 101 is mounted on a pivot member 103 and the forward end of the lever 101 is rockably secured to a pin or pivot member 104 carried by the slide or plunger 30 between the two bearing members 31 and 32. The rear or free end of the rock lever 101 slidably engages the marginal edge portion of a lever operating cam 105 which is fixed to the shaft 95. The cam 105 is so constructed that the slide or plunger 30 will be moved downwardly relatively fast and will be held in its

lowermost position for a short period and will then be moved upwardly and maintained in its uppermost position for another period in order to permit the hereinafter described operations to take place with respect to the bag.

The combined bag closing and folding mechanism 21 comprises a pair of rock levers 106 and 107 which are provided with bearings 108 and 109, respectively, engaging shafts 110 and 111, respectively. The shafts 110 and 111 are rotatably carried by a forwardly projecting bracket or arm 112 forming part of the frame structure 27. The rock lever 106 is provided with a yoke or U-shaped lower portion 113 and the lever 107 is provided with a similar yoke or U-shaped lower portion 114.

The lever 106 at the lower end thereof has rotatably mounted thereon a half round shaft 115. The yoke member 113 has fixed thereto a pair of semi-cylindrical bearing parts 116 which at one end thereof are provided with a flange 117 engaging against the outer edge of a yoke arm 113. The opposite end of the bearing part 116 is provided with a flange 118 having a groove or guide channel 119 therein facing the opposite arm of the yoke 113. The shaft 115 is provided with a pair of half round flanges 120 each of which is provided with a key or locking member 121 engaging in a groove or channel 119. In this manner the shaft 115 will be rotatably supported in the lower portion of the yoke 113 so that this yoke 113 may be swung toward or away from the yoke 114.

A second half round shaft 122 is rotatably carried by the yoke 114 and rotatably engages a pair of semi-cylindrical bearing parts 123 carried by the arms of the yoke 114. The bearing parts 116 are fixed to the yoke 113 by fastening devices 124 and the bearing parts 123 are fixed to the arms of the yoke 114 by fastening devices 125. The bearing part 123 at its outer edge is provided with a flange 126 and is provided with a second flange 127 at its inner end. The flange 127 is provided with a half round channel or key-way 128 within which a key 129 carried by a flange 130 engages. The flange 130 is carried by the shaft 122 between the two arms of the yoke 114. There are two of these bearing parts 123 which are similar in every detail and the two channels 128 confront each other as shown in Figures 5 and 6 in the same manner that the two channels 119 of the two bearing parts 116 confront each other.

The shaft 115 at its inner end is provided with a combined bag mouth closing and folding arm 131 and the shaft 122 is provided with a complementary bag mouth closing and folding arm 132. These arms 131 and 132 extend horizontally beneath the plunger or slide 30 and when the two arms 131 and 132 are in operative position they are disposed directly beneath the slide 30 and beneath the opening members 43 and 53 and the folding members 67 and 68.

The opposite or outer end of the shaft member 115 has a semi-circular spur gear 133 fixed thereto and the opposite end of the shaft member 122 has a semi-circular spur gear 134 fixed thereto. When the two shaft members 115 and 122 are in confronting and contacting position with the lower ends of the levers 106 and 107 disposed in operative position, the semi-circular gear members 133 and 134 form a complete split gear.

The yoke 113 adjacent the lower portion thereof and above the shaft 115 has a shaft 135

rotatably mounted in bearings 136 which are carried by the yoke 113. A gear 137 is fixed to the shaft 135 and meshes with the semi-circular gear 133 and also with the semi-circular gear 134 when these two gear parts are partially rotated as will be hereinafter described. In order to provide a means whereby the two yokes 113 and 114 may be held against edgewise movement relative to each other, I have provided a pair of arms 138 which are fixed to the yoke 113 and which slidably engage the confronting edges of the yoke 114 as shown in Figure 2. A sprocket 139 is fixed to the shaft 135 and has a chain 140 trained thereover. The chain engages about a sprocket 141 fixed to the shaft 110. A gear 142 is fixed to the shaft 110 and meshes with a gear 143 which is fixed to the shaft 111. The shaft 111 has a sprocket 144 fixed thereto about which a chain 145 engages. The chain 145 is also trained over a sprocket 146 secured to a shaft 147 which is journaled in a bearing 148 carried by a supporting arm or bracket 149. The arm or bracket 149 is carried by the rear frame structure 27 and is positioned above the pocket or arm 112. A gear 150 is fixed to the shaft 147 and is adapted to mesh with teeth 151 carried by a fragmentary gear 152. The gear 152 is mounted on a shaft 153 rotatably carried by the bracket structure 149 forwardly of the shaft 147. The teeth 151 are so arranged on the gear member 152 that they will mesh with the teeth of the gear 150 so as to rotate this gear 150 through about one-half turn for each complete rotation of the gear member 152 and thus rotate the shaft members 115 and 122 for a half revolution. The rotation of shaft members 115 and 122 to a half turn will effect transfer of the shaft member 115 to the yoke 114 and similarly effect transfer of the shaft 122 to the yoke 113. This transfer will occur for each half revolution of the two shafts 115 and 122.

A shaft 154 is journaled in bearings 155 carried by the forward ends of the brackets 149 and a gear 156 is fixed to the shaft 154. The gear 156 meshes with a gear 157 which is fixed to the shaft 153. A lever operating cam 158 is fixed to the shaft 154 and engages the upper portion of the lever 107. A second cam 159 is fixed to the shaft 153 and engages the upper portion of the lever 106. The levers 106 and 107 are yieldably held into engagement with the marginal portions of the cams 158 and 159 by means of springs 160 which at one end are secured to an arm 161 carried by the lever 106 and to an arm 162 carried by the lever 107.

A sprocket 163 is fixed to the shaft 153 and a chain 164 is trained over the sprocket 163. The chain 164 is also trained over a sprocket 165 which is fixed to the shaft 99.

The sealing mechanism 22 comprises a frame structure generally designated as 166 which is secured to the frame structure 27 at the end thereof opposite from the bag closing and folding structure 21. The frame structure 166 comprises outwardly extending supporting members 167 and upwardly projecting supports 168. A pair of yokes or rock levers 169 and 170 are rockably carried by the frame structure 166, the yoke 169 being rockably mounted on a shaft 171 which engages through a pair of ears 172 fixed to the yoke 169 intermediate the ends thereof and this shaft 171 is secured to the frame structure 166. The yoke 170 is provided with a pair of rearwardly projecting ears 173 through which a shaft 174 engages. The shaft 174 is secured to the

frame structure 166. The upper end of the yoke 169 is preferably bifurcated as at 175 and the roller 176 engages between the bifurcations 175 being rotatably mounted on a shaft or pin 177. The yoke 170 at its upper end is bifurcated as at 178 and a roller 179 is disposed between the bifurcations 178 and is rotatably mounted on a shaft or pin 180.

A cam shaft 181 is rotatably carried by the frame members 168 and a cam member 182 is fixed to the shaft 181 and engages between two rollers 176 and 179 so as to force the upper ends of the yokes 169 and 170 apart and thus cause the lower ends of these yokes or levers to be moved together or to an operative position. A spring 183 is secured at one end to the yoke 169 above the pivot 171 and at the other end is secured to the yoke 170 above the pivot 174 and acts to constantly maintain the rollers 176 and 179 in contact with the cam 182. A sprocket 184 is fixed to one end of the cam shaft 181 and a chain 185 is trained over the sprocket 184. The chain 185 is also trained over a sprocket 186 which is mounted on the shaft 91.

An elongated electrically heated sealing element 187 is carried by the yoke 169 at the lower end thereof and is adapted to be connected by wires 188 to a suitable source of electric current supply. The heating and sealing element 187 is provided with a pair of forwardly projecting pins or slide members 189 which are slidably through the two arms forming the lower end of the yoke 169 and a spring 190 engages about each pin or slide member 189 and at one end bears against the forward side of the sealing element 187 and at the other end bears against the inner face of one of the yoke arms.

One element 191 of a date stamp is carried by the lower side of the sealing element or member 187.

A second or complementary sealing member 192 is disposed in operative relation with respect to the sealing member or element 187, being provided with a pair of supporting pins 193 which slidably engage through the two arms forming the yoke 170. A spring 194 engages about a supporting member 193 and at one end bears against the rear side of the sealing element 192 and at the opposite end bears against the forward side of a yoke arm 170. A cotter pin or stop member 195 is secured to a supporting member 193 and limits the forward movement of the supporting member 193. A stop member 196 engages a supporting member 189 and limits the rearward movement of the supporting member 189. The sealing member 192 is provided with another dating element 197 which is adapted to confront the dating element 191 so as to date stamp the bag B simultaneous with the sealing of the folded mouth of the bag.

In order to provide a means whereby the filled bags are initially moved to a position for action by the combined opening and folding mechanism 20 and the combined closing and folding mechanism 21 and subsequently shifted to the sealing mechanism 22, I have provided a conveyor structure comprising an endless flexible conveyor element 198 in the form of a chain which engages about a driving sprocket 199 and idler sprockets 200, 201 and 202. The sprocket 199 is mounted on a drive shaft 203 which is journaled vertically relative to the table 25. The shaft 203 is journaled in a bearing 204 carried by a conveyor frame structure 205. The frame structure 205 is disposed over the table 25 and the conveyor

member 198 is disposed in parallel relation to and vertically spaced above the table 25. The conveyor member 198 is provided with a plurality of bag receiving pockets 206 which are secured in outwardly spaced relation to the conveyor member 198 by a supporting means 207. These bag receiving pockets 206 are spaced apart a distance substantially equal to the distance between the bag opening and folding structure 20 and the sealing structure 22.

The lower end of the drive shaft 203 has a bevel gear 208 fixed thereto which meshes with a bevel gear 209 carried by a rearwardly extending shaft 210. The shaft 210 is journaled in bearings 211 carried between base structure 26 and the rear end of the shaft 210 is provided with a rear bevel gear 212 meshing with a bevel gear 213 carried by a rear shaft 214. The shaft 214 at the opposite end is provided with a second bevel gear 215 which meshes with a bevel gear 216 mounted on the lower end of a vertical shaft 217. The shaft 214 is journaled in bearings 218 fixed to the rear of the frame structure 27. The upper end of the vertical shaft 217 has a bevel gear 219 fixed thereto meshing with a bevel gear 220 mounted on a drive shaft 221. The shaft 221 is journaled in bearings 222 carried by the frame structure 27 at the rear thereof.

A Geneva gear 223 is fixed to the shaft 221 and an operating member 224 is fixed to the shaft 89. The operating member 224 comprises a disc 225 and a roller 226 carried by a supporting arm 227 which is fixed to the disc 225. The roller 226 is adapted to engage in a slot 228 of the Geneva gear 223 so that the shaft 221 will be given substantially a quarter turn upon each complete turn of the operator 224. Each quarter turn of the shaft 221 will likewise effect a quarter turn of the driving sprocket 199 and thus move a bag receiving pocket 206 for the desired distance.

A second table 229 is disposed above and in parallel relation to the table 25 being supported by supporting members 230 which are secured to the table 25 and to the table 229. The table 25 immediately below the bag opening and folding mechanism 20 is provided with a rectangular opening 231. A bag elevator 232 is adapted in one position thereof to extend into the opening 231 and in another position thereof to be raised to a point where the upper surface thereof is flush with the second table 229. The elevator 232 comprises a platform 233 mounted on a stem 234 which extends downwardly through the opening 231 and through a guide 235 carried by the base structure 26. The stem 234 at its lower end is bifurcated as at 236 and the forward end of an elevator operating lever 237 engages between the bifurcations 236. A pin 238 extends between the bifurcations 236 below the lever 237 so that rocking movement of the forward end of the lever 237 will effect upward or downward movement of the elevator 232. The rear end of the elevator operating lever 237 is mounted on a pivot 239 carried by a depending support 240 fixed to the base structure 26.

A lever 241 is rockably mounted on a pivot 242 carried by the guide structure 31, the pivot 242 engaging through a bearing or support 243 which is fixed to the guide 231. The rear end of the rock lever 241 slidably engages the periphery of a cam 244 which is fixed to the shaft 95 and which is disposed closely adjacent the cam 105. The cam 244 is provided with a relatively long dwell portion which is adapted to

hold the lever 241 in an uppermost position for the greater portion of the rotation of this cam 244. The lever 241 is connected to the elevator lever 237 by means of a tie rod 245. The tie rod 245 at its upper end is provided with a coupling member 246 engaging a pivot 247 which extends through the lever 241. The lower end of the tie rod 245 has a coupling member 248 secured thereto which engages through an opening 249 provided in the table 25. The coupling member 248 is connected to the lever 237 by means of a pivot 250.

In Figure 17 there is disclosed a duplex machine embodying this invention wherein a combined bag opening and folding mechanism 20a is provided which is similar in every detail to the mechanism 20. A bag closing and folding mechanism 21a is associated with the opening and folding mechanism 20 and is similar in every detail to the closing and folding mechanism 21. A bag sealing mechanism 22a is also associated with the mechanisms 20a and 21a and a conveyor or bag shifting mechanism 23a is disposed over a table structure 25a. The mechanisms 20a, 21a, 22a, and 23a are operated in the same manner and by the same mechanism as that shown in Figure 1 and the detailed description of the individual parts associated with these mechanisms will apply equally as well to the bag opening mechanism and folding mechanism 20a, the bag closing and folding mechanism 21a, the bag sealing and dating mechanism 22a and the bag shifting mechanism 23a. In the present instance, however, a second bag opening and folding mechanism 20b is mounted on the frame structure 21a which is enlarged laterally to support the mechanism 20b. The mechanism 20b is similar in every detail to the mechanism 20 and the description of the mechanism 20 will apply in every detail to the mechanism 20b. A second sealing mechanism 22b is disposed laterally of the opening and folding mechanism 20b and is similar in every detail to the mechanism 22. The detailed description of the mechanism 22 will apply equally as well to the detail construction of the sealing and dating mechanism 22b.

The bag closing and folding mechanism 21a in the present instance is provided with a second pair of bag closing and folding members 131b which are mounted on shaft extensions 115b. The closing and folding mechanism 21b is provided with folding and closing members 131a similar to the two folding members 131 and 132 which are mounted on the shafts 115a. There are two of these shaft members 115a and also two of the shaft members 115b which are integral with the shafts 115a and are similar to the two shafts 115 and 122. The folding and closing members 131b are positioned beneath the lower end of the opening and closing mechanism 20b and are positioned above a conveyor mechanism 23b similar in every detail to the conveyor or bag shifting mechanism 23. The conveyor mechanism 23b is adapted to operate in a direction reverse from the conveyor mechanism 23a.

In the use and operation of this machine the initially filled bags B are placed in the receivers 206 at a point forwardly of the opening and folding mechanism 202. The bottom of the bag B is adapted to slide over the top of the table 25 and when the pocket or receiver 206 is moved beneath the opening and folding mechanism 20, the elevator 232 is in a position with the up-

per surface thereof flush with the surface of the table 25. Rotation of the shaft 95 by means of the chain 97 will cause the rear end of the lever 101 to be moved upwardly by engagement with the cam 105 so as to rock the forward end of the lever 101 downwardly and move therewith the slide or plunger 30. At this time the bag opening fingers 43 and 53 will be in the position shown in Figure 3, wherein these fingers are in downwardly convergent relation so that they can engage within the at least partially opened mouth of the bag mouth. At this time also the bag closing and folding members 131 and 132 are in the position shown in Figure 5. In this position they are out of engagement with the bag B. Simultaneous with the downward movement of the plunger or slide member 30, the elevator 232 will be moved upwardly to the position shown in Figure 3. This movement is effected by upward rocking of the lever 241 by means of the cam 244. Upward movement of the lever 241 will lift the lever 237 which will bring the elevator platform 233 flush with the upper surface of the secondary table 229. The elevator platform 233 will be maintained in its uppermost position until after the bag mouth has been opened and the bag closing members 131 and 132 have been moved into engagement with the mouth end of the bag.

After the bag opening members 43 and 53 are projected interiorly of the mouth end of the bag, the cam members 82 and 86 will rock the levers 35 and 36 so as to move the bag opening members 43 and 53 apart. Coincident with the outward movement of the opening members 43 and 53, they will be partially rotated by sliding engagement of the arms 46 and 56 with the cams 49 and 59. Also simultaneous with the outward swinging of the bag opening members 43 and 53, the cams 73 and 78 will swing the levers 63 and 64 inwardly at their lower ends so that the folding members 67 and 68 which are outside of the bag mouth will be swung inwardly to substantially the position shown in Figure 5a. This will form a longitudinal and inwardly projecting fold on opposite sides of the bag B with the fingers 43 and 53 holding the remaining sides of the bag taut.

After the bag mouth has been opened and a pair of inwardly projecting folds formed therein as shown in Figure 5a the yokes 113 and 114 will be moved toward each other so as to thereby bring the closing and folding members 131 and 132 against opposite sides of the bag B. At a time just prior to the closing of the mouth and of the bag, the cam 105 will lift the plunger 30 so as to withdraw the bag opening members 43 and 53. This withdrawal is effected at a time which will prevent the folded portions of the bag from returning to normal. The yokes 113 and 114 are moved at their lower ends toward each other by the cams 158 and 159 and these cams are provided with a relatively long dwell period which will hold the lower ends of the yokes 113 and 114 together and bring the shaft sections 115 and 122 into contacting relation. In Figure 6, the closing position of the bag B is shown with the two shaft sections 115 and 122 in contacting relation.

When the mouth of the bag has been closed to the position shown in Figure 6, the teeth 151 of the gear member 152 will engage the gear 150 so as to rotate the shaft 147. This rotation will be a rotation through an arc of 180° or one-half turn so that the gear train connected to the gear 137 will be rotated for one-half revolution. The half

turn of the gear 137 will cause the gear sections 133 and 134 to make one-half turn and this will effect a transfer of the shaft 115 from the yoke 113 to the yoke 114. The shaft 122 will also be transferred from the yoke 114 to the yoke 113.

At this time the bag closing members 131 and 133 will be given one-half turn in bag closing position so as to form the transverse fold shown in Figure 14.

When the bag B is formed with the transverse fold F shown in Figure 14, the Geneva gear operating member 224 will effect a quarter turn of the shaft 221. This quarter turn will be communicated to the shaft 203 which will rotate the driving gear 199 for one quarter turn and move the pocket or bag receiving member 206 from the raised platform or elevator 232 over the secondary table 229 and beneath the bag sealing mechanism 22. When the bag closing members 131 and 132 are given one-half turn so as to form the transverse fold F, the bag B will be partially raised relative to the carrier or receiver 206 so that the bag B will be substantially entirely suspended from the bag closing and folding members 131 and 132.

At this time the cam 244 will lower the elevator 232 to a position for receiving a succeeding carrier or bag receiving member 206.

The lateral movement of the bag in a carrier or pocket 206 is effected while the folded bag mouth is still engaged with the closing and folding members 131 and 132. These members are of yieldable construction so that they will readily release the folded end of the bag upon lateral movement of the associated carrier 206. The quarter turn of the driving gear 199 will bring the folded bag mouth between the two sealing members 187 and 192 which at this time are moved to a sealing position under the action of the cam 182. The sealing members 187 and 192 will effectively seal the folded portion F of the bag mouth under the heat of these sealing members so that when the conveyor 198 is again moved after the sealing members 187 and 192 have been moved apart by the cam 182, the mouth end of the bag will be effectively closed.

By forming a transverse fold at the mouth end of the bag, the closing and folding mechanism hereinbefore described will not only close the mouth of the bag but will also have a tendency to pack the material in the bag as the length of the bag is reduced by the formation of the fold F. After the carriers 206 pass from beneath the sealing mechanism 22, the bags may drop downwardly into a suitable collector or receiver.

In Figures 18 and 19, there is disclosed a modified form of sealing structure which is adapted to be associated with the bag opening and folding mechanism 20 and the bag mouth closing and folding mechanism 21. This rotary sealing mechanism 22c is to be substituted for the pincher sealing mechanism 22 and comprises a plurality of complementary electrically heated segmental sealing members 251 and 252 which are carried by gears 253 and 254 respectively, which mesh with each other. Gear 253 is mounted on a driving shaft 255 and gear 254 is mounted on an idler shaft 256. Shaft 255 is adapted to be operatively connected to the sprocket 184 by a suitable gear train, such as a pair of bevelled gears (not shown) so that the gears 253 and 254 may be rotated at the proper time in association with the balance of the closing and folding mechanism.

What I claim is:

1. A bag closing and sealing machine, comprising means engageable within the mouth of a bag for holding the mouth in an open and taut condition, oppositely movable means engageable with the bag exteriorly thereof for forming a pair of opposed inwardly projecting folds, means engageable with the bag mouth for compressing the same, means engageable with said compressing means to partially rotate the compressing means and to thereby form a closed reverted mouth, means for shifting the bag lengthwise of said compressing means while the bag is engaged with said compressing means, and means for sealing the reverted bag mouth.
- 15 2. A bag closing and sealing machine comprising bag mouth opening means, means for folding a pair of opposed walls of the bag inwardly, yieldable means compressing the folded walls and the other walls together, means engageable with said compressing means for rotating said compressing means to thereby form a reverted compressed mouth, means for shifting the bag while the mouth is engaged with said compressing means, and means for sealing the reverted compressed mouth.
- 20 3. A bag closing and sealing machine comprising a frame, vertically movable means in said frame engageable with the bag mouth for opening the same, operating means for said opening means, a horizontally movable bag carrier, a bag elevator below said carrier and confronting said first means, means for raising said elevator simultaneously with the lowering of said first means, a pair of oppositely disposed folding fingers, means for moving said folding fingers toward each other to thereby fold a pair of opposed walls inwardly, a pair of compressing fingers, means active after said folding fingers have folded said pair of opposed walls for compressing the folded walls and the remaining walls together, and means active after said walls have been compressed together for partially rotating said compressing fingers to thereby form a reverted closed mouth.
- 30 4. A bag closing and sealing machine comprising a vertically movable plunger, a pair of vertically rockable levers carried by said plunger, a pair of horizontally swingable bag mouth opening fingers carried by each lever, means engaging said levers constantly urging said levers to maintain said fingers in an inoperative position with the lower ends of one pair of said fingers closely adjacent the lower ends of the other pair of fingers, a second pair of levers, means mounting said second pair of levers for vertical rocking movement at right angles to said first levers, a folding finger carried by each of said second pair of levers, cam actuated means for moving said plunger and for holding said plunger in a lower operative position or an upper inoperative position, means active when said plunger is in a lower operative position for swinging said first levers and bag opening fingers to a bag opening position, means active when said bag opening fingers are in a bag opening position for rocking said second levers and folding fingers inwardly to thereby form an inwardly extending fold in each of a pair of opposed sides of the bag, means active upon initial movement of said plunger and said bag opening and folding fingers to an inoperative position for compressing the mouth of the bag, means for reverting the compressed bag mouth, and means for sealing the reverted and compressed bag mouth.
- 40 5. A bag closing and sealing machine comprising bag mouth opening means, means for folding a pair of opposed walls of the bag inwardly, yieldable means compressing the folded walls and the other walls together, means engageable with said compressing means for rotating said compressing means to thereby form a reverted compressed mouth, means for shifting the bag while the mouth is engaged with said compressing means, and means for sealing the reverted compressed mouth.
- 50 6. A bag closing and sealing machine comprising a frame, vertically movable means in said frame engageable with the bag mouth for opening the same, operating means for said opening means, a horizontally movable bag carrier, a bag elevator below said carrier and confronting said first means, means for raising said elevator simultaneously with the lowering of said first means, a pair of oppositely disposed folding fingers, means for moving said folding fingers toward each other to thereby fold a pair of opposed walls inwardly, a pair of compressing fingers, means active after said folding fingers have folded said pair of opposed walls for compressing the folded walls and the remaining walls together, and means active after said walls have been compressed together for partially rotating said compressing fingers to thereby form a reverted closed mouth.
- 60 7. A bag closing and sealing machine comprising bag mouth opening means, means for folding a pair of opposed walls of the bag inwardly, yieldable means compressing the folded walls and the other walls together, means engageable with said compressing means for rotating said compressing means to thereby form a reverted compressed mouth, means for shifting the bag while the mouth is engaged with said compressing means, and means for sealing the reverted compressed bag mouth.
- 70 8. A bag closing and sealing machine comprising bag mouth opening means, means for folding a pair of opposed walls of the bag inwardly, yieldable means compressing the folded walls and the other walls together, means engageable with said compressing means for rotating said compressing means to thereby form a reverted compressed mouth, means for shifting the bag while the mouth is engaged with said compressing means, and means for sealing the reverted compressed bag mouth.
- 80 9. A bag closing and sealing machine comprising bag mouth opening means, means for folding a pair of opposed walls of the bag inwardly, yieldable means compressing the folded walls and the other walls together, means engageable with said compressing means for rotating said compressing means to thereby form a reverted compressed mouth, means for shifting the bag while the mouth is engaged with said compressing means, and means for sealing the reverted compressed bag mouth.
- 90 10. A bag closing and sealing machine comprising bag mouth opening means, means for folding a pair of opposed walls of the bag inwardly, yieldable means compressing the folded walls and the other walls together, means engageable with said compressing means for rotating said compressing means to thereby form a reverted compressed mouth, means for shifting the bag while the mouth is engaged with said compressing means, and means for sealing the reverted compressed bag mouth.

prising means for holding the mouth of the bag open, means for forming a fold on opposed sides of the open bag mouth, a pair of parallel bag mouth compressing fingers, means for moving said fingers in parallelism to a bag mouth compressing position, means active when said fingers are in compressing position for partially rotating said fingers to thereby form a fold at the mouth end of the bag, a pair of sealing members, operating means for said sealing members, and means active after said compressing fingers have moved to a compressing position for moving the bag to a position for said sealing members acting on the compressed portion of the bag.

6. A bag closing and sealing machine comprising means for opening the bag mouth, a pair of bag mouth closing members, a rock lever for each member, a pair of half round shafts secured to said closing members, a pair of semi-circular gears fixed one to each of said shafts, interengaging bearing members carried by each lever and each shaft, cam actuated means engaging said levers for rocking said levers to thereby effect engagement of said shafts and said semi-circular gears with each other, and means active when said shafts are in contacting relation for rotating said shafts to thereby transfer one shaft and its associated bearing from one lever to the other to thereby form a fold at the mouth end of the bag.

7. A bag closing and sealing machine comprising means for holding the bag mouth open and forming a longitudinal fold on opposed sides of the bag at the mouth end, means for initially closing the mouth end, means active on said closing means subsequently to the closing of the bag mouth forming a transverse fold across the mouth end, bag mouth sealing means, and shifting means for shifting the bag from said closing and folding means while engaged therewith in a plane parallel to said latter means to said sealing means for action on the folded mouth end by said sealing means.

8. A bag closing and sealing machine comprising an intermittently operable bag mouth opening means, an intermittently operable fold forming means for forming opposed inwardly directed folds at the mouth end of the bag, intermittently operable combined bag mouth closing and folding means operable to initially close the bag mouth and subsequently form a transverse fold across the closed bag mouth, intermittently operable sealing means, and means active after operation of said combined closing and folding means and while the folded bag mouth is engaged between said combined closing and folding means for shifting the bag to said sealing means for action thereon.

9. A bag closing and sealing machine comprising a table, a bag carrier movable in a plane parallel with and above said table, a vertically movable bag elevator carried by said table, a combined bag mouth opening and bag folding means above said elevator, means for simultaneously moving said elevator and said opening and folding means in opposite directions, an intermittently operable bag mouth closing means including means for actuating said closing means to thereby form a transverse fold at the mouth end of the bag, a bag mouth sealing means, and means for operating said bag carrier to move the bag from said closing means to said sealing means.

10. A bag closing and sealing machine comprising a table, a bag carrier movable in a plane

parallel with and over said table, a second table disposed above and parallel with said first table, a vertically movable bag elevator movable from a position with the upper surface thereof flush with said first table to a position flush with said second table, a bag mouth opening means above said elevator, intermittently operable means for simultaneously moving said elevator and said opening means in opposite directions, means engageable with the mouth end of the bag for forming a pair of opposed inwardly directed folds in the bag, intermittently operable means engageable with said bag opening means and said fold forming means for simultaneous operation thereby, an intermittently operable bag mouth closing means, operating means for actuating said bag closing means at substantially the time said bag opening means and said bag folding means are in operative position, said first named intermittently operable means acting to withdraw said bag opening and folding means from the bag mouth prior to the complete closing of the bag mouth, intermittently operable means operable when said closing means is in bag mouth closing position for partially rotating said closing means to thereby form a transverse fold at the mouth end of the bag, a bag mouth sealing means, and intermittently operable means for said carrier for initially moving a bag onto said elevator when said elevator is flush with said first table and subsequently moving the elevated bag onto said second table for operation thereon by said sealing means.

11. A bag closing and sealing machine comprising a combined bag mouth opening and fold forming means, a combined bag mouth closing and fold forming means, a bag mouth sealing means, means for shifting the bag from said closing and fold forming means to said sealing means, said bag mouth opening and fold forming means comprising a vertically slidable plunger, operating means for said plunger, a pair of rock levers carried by said plunger, a plurality of bag mouth opening members carried by said levers, a second pair of rock levers carried by said plunger and rockable at right angles to said first pair of levers, a fold forming member carried by each of said second levers, a cam carried by each of said first pair of levers engageable with said second levers to thereby rock said second levers simultaneous with the rocking of said first levers, and rotatable cam means engaging said first levers.

12. A bag closing and sealing machine comprising a combined bag mouth opening and fold forming means, a combined bag mouth closing and fold forming means, a bag mouth sealing means, means for shifting the bag from said closing and fold forming means to said sealing means, said bag mouth opening and fold forming means comprising a vertically slidable plunger, operating means for said plunger, a pair of rock levers carried by opposed sides of said plunger and each having a portion thereof projecting below said plunger, a pair of bag opening fingers carried by each lever, means securing said fingers to said levers for horizontal swinging movement, a second pair of rock levers carried by said plunger and rockable at right angles to said first pair of levers, a fold forming finger carried by each of said second pair of levers, a cam carried by each of said first pair of levers engageable with said second levers to effect rocking of said second levers upon rocking of said first levers, means for rocking said first

levers, and means carried by said plunger engageable with said bag opening fingers to thereby effect horizontal rocking thereof relative to said first levers simultaneous with the rocking of said first levers.

13. In a bag closing and sealing machine, means for initially closing the bag mouth and subsequently forming a fold transverse of the mouth end of the bag, said means comprising a pair of rockable levers each provided with a pair of spaced arms, means for rocking said levers, a half round shaft section carried by the arms of each lever, a fragmentary bearing element fixed to each arm, a pair of fragmentary bearing elements fixed to each shaft section, interengaging retaining means carried by the bearing elements on each arm and the bearing elements on each shaft for retaining a shaft section on a pair of arms when said arms and shaft sections are in spaced apart inoperative position, a combined bag closing and folding blade carried by each shaft section, a semi-circular gear carried by each shaft section, and intermittently operated means operatively connected to one of said semi-circular gears for partially rotating said shaft sections when said shaft sections are in contacting relation.

14. In a bag closing and sealing machine, a combined bag mouth closing and folding means comprising complementary shaft sections, intermittently operable swingable supporting means for said shaft sections, interlocking bearing elements carried by said shaft sections and said supporting means, combined bag mouth closing and folding members carried by said shaft sections, rotatable cam means engaging said supporting means to thereby effect rocking of the supporting means, complementary gear members carried by said shaft sections, and means operatively connected to at least one of said gear members for effecting partial rotation of said gear members.

15. In a bag closing and sealing machine, a bag mouth closing and reverting structure com-

prising a pair of combined bag mouth closing and reverting members, means swingably supporting said members in parallel relation for movement toward or away from each other, operating means for moving said members relative to each other, means for rotating said members relative to said supporting means through one-half turn when said members are in bag mouth closing position swung toward each other in a position to thereby revert the closed bag mouth, and means effecting a transfer of said members to opposed supporting means while said members are in a bag clamping position.

16. In a bag closing and sealing machine, a bag mouth closing and reverting structure comprising a pair of combined bag mouth closing and reverting members, means supporting said members in parallel relation for movement toward or away from each other, operating means for moving said members relative to each other, means for rotating said members through one-half turn when said members are in bag mouth closing position to thereby revert the closed bag mouth, and means for shifting the bag in a plane parallel with said members while said members are in bag mouth reverting position.

17. A bag closing and sealing machine comprising means for forming opposed folds in opposed sides of the bag, a pair of elongated flat bag mouth closing and folding members disposed in parallel relation, means supporting said members for movement toward or away from each other, a half round shaft secured to each member, a semi-circular gear fixed to each shaft, interengaging bearing members carried by each shaft and said supporting means, means for shifting said supporting means to dispose said shafts and said members with the flat faces thereof in confronting relation, and means active when said shafts are in confronting relation to effect partial rotation of said shafts to thereby fold the compressed bag mouth engaging between said members.

JOHN L. KNAPP.
